UNITED STATES PATENT OFFICE.

ERIC ZETTERQUIST, OF ESSINGTON, PENNSYLVANIA, ASSIGNOR TO WESTINGHOUSE ELECTRIC AND MANUFACTURING COMPANY, A CORPORATION OF PENNSYLVANIA.

TURBINE BLADING.

Application filed December 21, 1923. Serial No. 682,102.

To all whom it may concern:

Be it known that I, ERIC ZETTERQUIST, a citizen of the United States, and a resident of Essington, in the county of Delaware and 5 State of Pennsylvania, have invented a new and useful Improvement in Turbine Blading, of which the following is a specification.

My invention relates to turbine blading, 10 more particularly to that of the wide exhaust type, and it has for its object to provide blading structure of this type which has a plurality of circumferential groups of energy-abtracting elements which are 15 respectively supplied with motive fluid entering between the successive inlet edges of the blading structure so that the total passage area between the blading may be made equal to or less than the annulus inlet area, 20 whereby the energy of the entering motive fluid may be conserved as it passes between the blades.

Apparatus embodying features of my invention is illustrated in the accompanying 25 drawings, forming a part of this application, in which:

Fig. 1 is a detail view of a portion of a 30 turbine showing my improved blading structure applied thereto;

Fig. 2 is a sectional view taken along the line II—II of Fig. 1;

Fig. 3 is a sectional view taken along the line III—III of Fig. 1;

Fig. 4 is a view similar to Fig. 1 but 35 showing a modified form of my improved blading structure;

Fig. 5 is a sectional view taken along the line V—V of Fig. 4;

Fig. 6 is a sectional view taken along the 40 line VI—VI of Fig. 4;

Fig. 7 is a detail view showing a further modified form of my improved exhaust blading structure;

Fig. 8 is a sectional view taken along the 45 line VIII—VIII of Fig. 7; and

Fig. 9 is a sectional view taken along the line IX—IX of Fig. 7.

In the patents of Henry F. Schmidt, No. 1,469,965, issued October 9, 1923 and Alexander T. Kasley, No. 1,469,925, issued October 9, 1923, both of which are assigned to the Westinghouse Electric and Manufacturing Company, there is disclosed and claimed exhaust blading of the wide type

which is adapted to receive motive fluid at 55 one side and to discharge the same peripherally or peripherally and laterally. With blading of this type, however, the total passage area immediately before the energy-abtracting portions is much greater than the 60 total annulus area at the inlet edges of the blades. This increase in area from the inlet edges of the blades toward the energy-abtracting portions results in a diminution 65 in the velocity of motive fluid entering between the blades and, therefore, in a loss in energy of the motive fluid before it reaches the energy-abtracting portions of the blades. For example, if it is assumed that motive fluid is received between 70 the inlet edges of the wide blades at a velocity of 800 ft. per second and that the total of the inlet area is A and that the total of the cross sectional area of the passage immediately preceding the energy-abtracting portion is 2A, then it is obvious 75 that the velocity of the motive fluid will drop to 400 ft. per second; and, as the energy of motive fluid varies as the square of its velocity, it is apparent that, in the 80 example assumed, three-fourths of this energy is lost in passage between the blades.

Accordingly, it is the object of my invention to provide exhaust blading structure, 85 which is somewhat similar to the Schmidt and Kasley constructions aforesaid in that motive fluid is discharged peripherally or peripherally and laterally, but in which the blading structure is so designed that the total of the cross sectional areas of the 90 passages immediately preceding the energy abstracting portions of the blades is equal to or less than the total of the annulus area at the inlet edges of the blades, thereby avoiding the loss in velocity due to an 95 increase in the passage area between the blades from the inlet toward the outlet edges.

Referring now to the drawings for a better understanding of my invention, I show 100 in Figs. 1 to 3, an exhaust blade structure at 10, carried by a rotor 11 which is adapted to receive an annulus of motive fluid discharged by the fixed guide blades 12, carried by the cylinder or casing 13, and to 105 divide such motive fluid for discharge and energy abstraction both radially and axially.

The exhaust blade structure 10 comprises a plurality of cellular blade groups 14 each of which includes complementary blade elements 15 and 16 having outer contacting portions 17 and 18 which define nozzle or expansion passages 19 communicating with intergroup spaces 20 arranged between adjoining blade elements 15 and 16 of adjacent groups 14. The blade elements 15 and 16 of adjacent groups are preferably provided with contacting curved rib elements 21 which are adapted to change the direction of flow of motive fluid received in the passages 20 toward a radial direction for discharge by the expansion passages 19.

The complementary blade elements 15 and 16 with their contacting portions 17 and 18 of the cellular groups 14 define axially-arranged cellular passageways adapted to discharge motive fluid into nozzle or expansion passages at 24 defined by radially-arranged blade elements at 25. As shown in Fig. 3, the radially-arranged blade elements 25 are adapted to contact with blade elements 15 and 16 of adjacent cellular groups 14 in order to brace the blade elements 15 and 16 as well as to close the inter-group spaces 20 at the outer ends of the blades 15 and 16.

As the motive fluid discharged from the fixed guide blades 12 is divided by the blade elements 15 and 16 so that the motive fluid passing in alternate blade spaces is conducted to the independent rows of energy-absorbing elements, the latter may be so formed as to provide adequate discharge area at small leaving or exit angles thereby providing for high blade efficiency and, at the same time, the cross sectional areas of the passages between the blade elements immediately preceding the energy absorbing portions 19 or 24 may be maintained equal to or less than the corresponding inlet areas, thereby avoiding a loss in velocity energy and further increasing the efficiency of the turbine.

In Figs. 4, 5 and 6, I show a modified form of my exhaust blade structure in which the motive fluid discharged from the exhaust blades 12 is divided and discharged peripherally only for energy abstraction. In this modification, the exhaust blade structure comprises two rows of cellular blade groups at 27 and 28, the cellular blade groups being similar to those shown in Figs. 1, 2 and 3 and the elements thereof will be referred to by the same reference characters. The blade elements 14 of the row 27 define inter-group spaces 20 which communicate with expansion passages 19, the cellular passages 23 of the blade groups 14 of the row 27 register with the inter-group spaces 20 of the second row of cellular blade groups 28 and the latter inter-group spaces supply motive fluid to the expansion passages 19 of the second row.

It will, therefore, be apparent that in Figs. 4, 5 and 6, the motive fluid received from the fixed guide blades 12 is divided into a plurality of segmental portions by the blade elements of the first row of cellular groups 27, alternate segmental portions passing through the inter-group passages 20 and being expanded by the communicating nozzle passages 19 of the first row of blade groups 27 and the intervening segmental portions of motive fluid pass through the cellular passages 23 of the first row of blade elements 27 and into the inter-group passages 20 of the second row of cellular blade groups 28 for expansion by the passages 19 thereof.

In Figs. 7, 8 and 9, I show a further modified form of my exhaust blading structure in which the motive fluid discharged from the fixed guide blades 12 is divided into three groups of segmental portions for discharge and energy abstraction by the energy-absorbing portions of the rows of blade elements at 29, 30 and 31.

This modification comprises features shown in Figs. 1 and 4, in that the peripheral discharge of motive fluid by two rows of energy-absorbing elements and the discharge axially by one row of energy-absorbing elements is provided for. Each of rows 29 and 30 comprises cellular groups 32 composed of blade elements 33, 34 and 35 having contacting portions 36, 37 and 38 at outer ends which define expansion passages 39 for the inter-group spaces 40 arranged between the blades 33 and 35 of adjacent groups 32. The adjacent blades 33 and 35 are preferably provided with curved guide ribs 41 to change the direction of flow of motive fluid to a peripheral direction for discharge through expansion passages 39. Cellular passageways 42 and 43 are defined, respectively, between the blade elements 33 and 34 and 34 and 35 of each cellular group 32.

The cellular groups comprising the first and second rows 29 and 30 are circumferentially displaced so that the cellular passages 42 of the groups of the row 29 communicate either with the inter-group spaces 40 or with the cellular passages 43 of the second row 30 of cellular blade groups 32. With the cellular passageways 42 of the first row communicating with passages of the second row in the manner stated, the cellular passages 43 of the first row would communicate either with the cellular passages 42 of the second row 30 or with the inter-group spaces 40 thereof. With either arrangement, cellular passages in the two rows of cellular blade groups are in registry and the blade elements 31 are arranged to define expansion passages 44 in communication therewith. As shown in Fig. 9, the radially-arranged blade elements 31 have

portions 45 and 46 which contact with the blade elements which define the cellular passages leading motive fluid to the expansion passages 44 between the radially-arranged 5 blade elements 31. In this modified form of my apparatus, therefore, the motive fluid is divided by the blade elements into segmental portions which are discharged successively by the expansion passages 39 of 10 the rows of blades 29 and 30 and by the expansions 44 defined by the blade elements 31.

In the modified form of my apparatus shown in Figs. 4, 5 and 6, the rows of blade elements 27 and 28 are alike; that is, the 15 blade elements 15 and 16 may be used in either row 27 or 28. Likewise, in Figs. 7, 8 and 9, the blade elements 33, 34 and 35 of the two rows 29 and 30 are interchangeable.

20 Apparatus made in accordance with my invention operates as follows: The annulus of motive fluid discharged from the fixed guide blades 12 is divided into an annular series of segmental portions by the wide 25 blade elements and the latter elements are so arranged and constructed that successive segmental portions of motive fluid flow respectively through a plurality of rows of energy-absorbing elements. The feature 30 of providing a plurality of rows of energy-absorbing elements for the motive fluid permits of such a choice of blade width and such a design of expansion passages for the energy-absorbing portions that adequate 35 discharge area is provided for at small angles and the cross sectional areas of the passages between the blade elements are maintained substantially constant so as to avoid a loss in velocity between the blades 40 before the motive fluid reaches the energy-absorbing portions. Therefore, my exhaust turbine blading is highly efficient both from the standpoint of providing adequate discharge area at small angles and from the 45 standpoint of avoiding a loss in velocity consequent upon increasing the passage area between the inlet and the energy-absorbing portions.

While I have shown my invention in several forms, it will be obvious to those skilled in the art that it is not so limited, but is susceptible of various other changes and modifications, without departing from the spirit thereof, and I desire, therefore, that 55 only such limitations shall be placed thereupon as are imposed by the prior art or as are specifically set forth in the appended claims.

What I claim is:—

60 1. In a turbine, an exhaust blade structure comprising a row of wide blade elements and a plurality of rows of energy-absorbing elements associated therewith, whereby the total cross sectional areas of the 65 passages between the inlet and the energy-

abstracting portions may be made not greater than the inlet areas between the blade elements.

2. In a turbine, an exhaust blade structure having a plurality of groups of energy-absorbing elements and means for dividing motive fluid into successive portions for the respective energy-absorbing elements. 70

3. In a turbine, an exhaust blade structure arranged to divide the motive fluid into groups of segmental portions and having a plurality of independent energy-absorbing elements for abstracting energy from the respective groups of segmental portions of the motive fluid. 75

4. In a turbine, an exhaust blade structure wherein the blades define successive passages leading to independent rows of energy-absorbing elements. 80

5. In a turbine, an exhaust blade structure comprising a plurality of groups of blade elements cooperating to define energy-absorbing portions for the motive fluid passing between the groups and one or more rows of energy-absorbing elements for the motive fluid passing between the blade elements of said groups. 85

6. In a turbine, an exhaust blade structure having a plurality of annularly-arranged groups of energy-absorbing elements successively arranged along the turbine axis and means for dividing the motive fluid into successive portions for discharge to the respective groups of energy-absorbing portions. 95

7. In a turbine, an exhaust blade structure having an annular series of blade elements, a plurality of annular rows of energy-absorbing elements, and means cooperating with said blade elements for dividing motive fluid into a plurality of segmental portions for discharge by the respective groups of energy-absorbing elements. 100

8. In a turbine, an exhaust blade structure having a circumferentially-arranged group of energy-absorbing elements, a radially-arranged group of energy-absorbing elements, and means for dividing the motive fluid into two groups of segmental portions and for conducting one group of segmental portions to the circumferentially-arranged energy-absorbing portions and the other group of segmental portions to the other energy-absorbing portions. 110

9. In an axial-flow turbine, an exhaust blade structure having separate groups of energy-absorbing elements, at least one of which discharges peripherally, and blade elements for dividing axially-discharged motive fluid into separate portions for action on the energy-absorbing elements. 115

10. In a turbine, an exhaust blade structure comprising a plurality of alternating and relatively-displaced energy-absorbing 125

130

elements, and blade elements defining alternate spaces communicating with said alternating energy-abstracting elements.

11. In a turbine, an exhaust blade structure comprising a plurality of blades arranged to receive motive fluid at one side, pairs of said blades contacting at their tips and defining expansion passages for the motive fluid passing between the pairs, and 10 axially-discharging energy-abstracting elements for motive fluid passing between the blades of the pairs.

12. In a turbine, a last row of moving wide blades adapted to receive motive fluid 15 at one side and to divide it into an annular series of segmental portions, a plurality of rows of energy-abstracting elements, and means for dividing the segmental portions of motive fluid into a plurality of groups 20 for discharge to the rows of energy-abstracting elements.

13. In a turbine, a row of wide blade elements adapted to divide motive fluid into an annular series of segmental portions, a 25 plurality of rows of energy-abstracting elements associated with the blade elements, and means associated with said blade elements for dividing the segmental portions between the rows of energy-abstracting elements, whereby the passages between the 30 blade elements may be so arranged that the cross sectional area thereof before the energy-abstracting elements is not greater

than the inlet area between the blade elements.

14. In a turbine, an exhaust blade structure comprising a row of cellular blade groups, defining inter-group and cellular segmental passages and peripheral expansion passages in communication with the 40 inter-group segmental passages, and energy-abstracting elements adapted to receive motive fluid from said cellular segmental passages.

15. In a turbine, an exhaust blade structure comprising a row of cellular blade groups defining inter-group segmental passages which communicate with peripheral 45 expansion passages and each group defining one or more cellular segmental passages, 50 and one or more rows of energy-abstracting elements for abstracting energy from said one or more cellular passages of said groups.

16. In a turbine, an exhaust blade structure comprising a plurality of rows of cellular blade groups which define segmental passages therebetween communicating with peripheral expansion passages and cellular segmental passages, the rows of groups being so arranged that the cellular passages 60 of a preceding row communicate with the inter-group passages of a succeeding row.

In testimony whereof, I have hereunto subscribed my name this 3rd day of December 1923.

ERIC ZETTERQUIST.
